UNITED STATES PATENT OFFICE.

CHARLES H. SMIRL AND FRED L. SMIRL, OF CRAIG, MISSOURI.

DESIGN FOR A PICTURE-FRAME.

SPECIFICATION forming part of Design No. 24,474, dated July 16, 1895.

Application filed June 11, 1895. Serial No. 552,486. Term of patent 14 years.

To all whom it may concern:

Be it known that we, CHARLES H. SMIRL and FRED L. SMIRL, citizens of the United States, residing at Craig, in the county of Holt and State of Missouri, have invented a new and original Design for a Picture-Frame, of which the following is a specification.

This invention relates to a new and original design for picture-frames; and it has for its object to provide a design of this character that shall be both useful and ornamental.

The leading feature of the design resides in a substantially-rectangular frame provided with a central rectangular figure bounded at the surface of the frame by a superficial rounded rib; a plain field between said rib and the outer edges of the frame; scalloped outer edges, said scalloped outer edges being formed by sigmoidal lines running from each corner to a central point between the corners and meeting at said central points and corners in a point to form re-entrant angles or V-shaped figures, and superficial globular-shaped projections located at both sides of said re-entrant angles or V-shaped figures.

In the drawings, Figure 1 is a perspective view of a picture-frame embodying the herein-described design. Fig. 2 is a front view of the same.

Referring to the accompanying drawings, the numeral 1 designates a substantially-rect-

angular picture-frame provided with a central rectangular figure 2, surrounded by rectangularly-arranged marginal spaces 3, which are bounded at the surface of the frame by a superficial rounded rib 4. Between the superficial rounded rib and the outer edges of the frame is formed a plain field 5, and said outer edges of the frame are scalloped. The scalloped outer edges of the frame are formed by sigmoidal lines 6 running from each corner to a central point between the corners and meeting at said central points and corners in a point to form re-entrant angles or V-shaped figures 7. At the surface of the frame the sigmoidal lines 6 are bounded by superficial rounded ribs 8, which connect the superficial globular-shaped projections 9 that are formed on the surface of the frame at both sides of said re-entrant angles or V-shaped figures.

What we claim is—

The design for a picture frame herein shown and described.

In testimony that we claim the foregoing as our own we have hereto affixed our signatures in the presence of two witnesses.

CHARLES H. SMIRL.
FRED L. SMIRL.
